UNITED STATES PATENT OFFICE.

EDWARD SALOMON BERGLUND, OF DJURSHOLM, SWEDEN.

MEANS FOR CONVERTING ZINC POWDER INTO FLUID ZINC.

Application filed February 2, 1922, Serial No. 533,701, and in Sweden February 22, 1921.

When extracting zinc and lead, from their ores especially according to electro-thermic methods, fluid metal is obtained in the condenser, as known, from the metal gases escaping from the reduction furnace, together with a metallic powder, the so-called poussiere, which must be subjected to a treatment in one manner or another in order to obtain fluid metal therefrom. No method of operation is available at present whereby the generation of powder is wholly obviated in the process.

For treating the powder many different methods and devices have been proposed. Among them there are devices, by means of which the powder is subjected to a mechanical treatment within the condenser, while still warm. Said treatment has been carried out according to hitherto proposed methods either by providing the condenser with a member, by the movement of which the powder has been turned over or shaken, or a treatment has been carried out by means of apparatus, placed within the furnace chamber. In apparatus of this latter kind screws or rolls or a vertical shaft provided with vanes, have been employed.

Said devices, however, in fact have only exerted a pressure on the metal powder, without agitating the same, which pressure has proved to be insufficient in practice for effectively converting the powder into metal, as for this purpose also the powder must be stirred and rubbed. The apparatus with the vertical shaft carrying vanes is affected with the inconvenience, that the stirring is very ineffective, mainly resulting in imparting a rotary motion to the powder, and that the bearing of the shaft soon becomes obstructed by metal condensed from the gases, so that the shaft cannot be rotated.

The present invention relates to a device by means of which the mixture of powder and fluid metal, formed in the condenser during the condensation, may be violently agitated within the condenser, being subjected partly to repeated lifting operations, so that the several particles may be effectively rubbed together.

On the accompanying drawing Fig. 1 is a vertical section of the lower part of a condenser for zinc-lead gases showing the stirring apparatus according to the present invention. Fig. 2 is a vertical section of the condenser at right angles to Fig. 1. Figs.

3-8 show several modified forms of the stirring members.

For obtaining the result above referred to the apparatus 1, by means of which the stirring operation is performed, are secured to horizontal shafts 2, which penetrate the condenser wall 3 at a point in the lower part of the condenser adjacent to the bottom of the same, so that the powder always covers the point, where the shafts 2 penetrate the condenser wall 3. By this means the metal vapours are prevented from penetrating the bearings, and from obstructing the same. The stirring members 1 consist of propeller shaped apparatus of fire proof material or other material resisting the influence of heat and fluid zinc or lead or zinc-lead alloy.

The mixture of fluid metal and powder falling down from the upper part of the condenser, is immediately treated by the stirring members 1, and the generation of metal from the powder is moreover promoted thereby, as the metal, formed in the open condenser chamber is not separated from the powder, but partakes in the stirring operation established by the stirring members. The several vanes or spokes of the propeller shaped stirring members may be unequal as to their form, so that the successive vanes or spokes do not follow the same track, whereby the stirring operation is promoted.

Fig. 3 shows the form of the vane 4 which is shown in Fig. 4 in side view, whereas Fig. 5 shows the form of the vane 5 in plan. The vane 4 in Fig. 4 may also have the form shown in full lines in side view in Fig. 6, whereas the vane 5 has the form shown in dotted lines in Fig. 6. Figs. 7 and 8 show in side view and end view one form of a stirring member, by means of which an alternative displacement of the powder sideways is established simultaneously with the stirring operation owing to the rotation of the vanes. A multitude of other forms than shown on the drawing may be used. The members receive their motion from a shaft not shown outside of the condenser. By varying the direction of motion, speed, size and form of the several stirring members, the greatest possible effect may be obtained. The shaft 2 is journaled outside the wall 3 of the condenser, through which the shafts 2 passes, as shown on the drawing. This, however, is not essential. Manholes may be made in the wall 6 opposite the stirrers.

through which the stirring members may be accessible or may be exchanged.

The fluid metal formed by the condensation and the treatment of the powder, is gathered on the bottom of the condenser, from which it is tapped.

As owing to several circumstances in extracting zinc and lead from ore in the electro-thermic method part of the powder is usually oxidized, the whole amount of the powder cannot be converted into fluid metal. The part of the same, which when passing the stirring members, is not converted into fluid metal, may be transported out of the condenser by means of a screw 7. By tapping the metal in shorter or longer intervals the powder can be subjected to the treatment during a shorter or longer time, in view of the fact that the powder, floating on the surface of the metal bath, is raised towards the stirring members and can be kept there for any desired time.

Having now described my invention, what I claim as new and desire to secure by Letters Patent is:—

1. In a device for extracting zinc and lead, a condenser, and a plurality of stirring members, consisting of rotary vanes, placed in spaced relation to one another in the lower part of the condenser, receiving the metal powder, formed during the condensation, to violently agitate said powder.

2. In a device for extracting zinc and lead,

a condenser, and a plurality of stirring members, consisting of rotary vanes of unequal form, placed in spaced relation to one another on horizontal shafts, embedded in the metal powder formed during the condensation, to violently agitate said powder.

3. In a device for extracting zinc and lead, a condenser, and a plurality of stirring members, consisting of rotary vanes, placed in spaced relation to one another in groups, each mounted on a horizontal shaft, embedded in the metal powder gathered at the bottom of the condenser, to violently agitate said powder.

4. In a device for extracting zinc and lead, a condenser, and a plurality of groups of stirring members, each group consisting of a plurality of rotary vanes, placed in spaced relation to one another on a horizontal shaft, embedded in the metal powder gathered at the bottom of the condenser, to violently agitate said powder.

5. In a device for extracting zinc and lead, a condenser, and a plurality of rotary vanes, placed in spaced relation to one another in the lower part of condenser, and formed so as to establish an alternating displacement in opposite side directions of the metal powder, formed in the condenser, to violently agitate said powder.

In testimony whereof I have signed my name to this specification.

EDWARD SALOMON BERGLUND.
